(57) **CLAIM**

The ornamental design for a lighting device, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1. is a front perspective view of the front, right, and top sides of a lighting device showing our new design;
FIG. 2. is a front view thereof;
FIG. 3. is a rear view thereof;
FIG. 4. is a top plan view thereof, a bottom plan view being a mirror image thereof;
FIG. 5. is a right side view thereof, a left side view being a mirror image thereof;
FIG. 6. is an enlarged end view showing cross-sectional end face only at a cut part 6-6., with partially omitting the interior mechanism;
FIG. 7. is an enlarged end view showing cross-sectional end face only at a cut part 7-7., with partially omitting the interior mechanism; and,
FIG. 8. is a reference perspective view showing a light emitting state.
